(57) **CLAIM**

The ornamental design for a bathtub closure, as shown and described.

DESCRIPTION

FIG. 1 is a front perspective view of a first embodiment of a bathtub closure, showing our new design;
 FIG. 2 is a front elevation view thereof;
 FIG. 3 is a rear elevation view thereof;
 FIG. 4 is a left elevation view thereof;
 FIG. 5 is a right elevation view thereof;
 FIG. 6 is a top plan view thereof;
 FIG. 7 is a bottom plan view thereof;
 FIG. 8 is a front perspective exploded view thereof;
 FIG. 9 is a front perspective view of a second embodiment of the bathtub closure;
 FIG. 10 is a front elevation view thereof;
 FIG. 11 is a rear elevation view thereof;
 FIG. 12 is a left elevation view thereof;
 FIG. 13 is a right elevation view thereof;
 FIG. 14 is a top plan view thereof;
 FIG. 15 is a bottom plan view thereof; and,
 FIG. 16 is a front perspective exploded view thereof.
 The broken lines in the figures illustrate unclaimed portions of the bathtub closure.

1 Claim, 12 Drawing Sheets
